UNITED STATES PATENT OFFICE.

JOHN P. SHERWOOD AND SYLVESTER H. HUNTER, OF NEW BRIGHTON,
PENNSYLVANIA.

DESIGN FOR A PACKING-JAR.

SPECIFICATION forming part of Design No. 24,794, dated October 29, 1895.

Application filed May 18, 1895. Serial No. 649 840. Term of patent 3½ years.

To all whom it may concern:

Be it known that we, JOHN P. SHERWOOD and SYLVESTER H. HUNTER, citizens of the United States, residing at New Brighton, in the 5 county of Beaver and State of Pennsylvania, have invented and produced a new and original Design for a Packing-Jar; and we do hereby declare the following to be a full, clear, and exact description of the invention, such 10 as will enable others skilled in the art to which it appertains to make and use the same, reference being had to the accompanying drawing, and to the letters of reference marked thereon, which forms a part of this 15 specification.

The leading feature of our design consists in giving such a configuration to a packing-jar that the lower and major part of the jar shall present the ordinary and plain cylindrical outline of a jar, while the upper and smaller part appears in a series of concaved and tapering rings crowned by a flat top and united to a jar-handle, which exhibits itself as 20 an integral and ornamental part of the whole 25 design, which we now proceed to describe in detail.

A is the cylindrical body of the jar; B, a circular, concaved, and upwardly-tapering re-

cess therein; C, a second circular and concaved recess rising immediately from the first 30 and finished by a vertical shallow circular rim d, within which appears the lid. This lid E has its upper part g concaved and tapered upward. The top and central part of the lid is shown depressed into a sloping circular chamber h, within which is the knob I, presenting its flat top as flush with the top line of the lid. 35

In the recess B are seen two oppositely-placed thin and pierced lugs K, flush with the 40 vertical contour of the jar-body, and these appear as engaged with a bail L, having its handle m seated within the recess B, and by the described formation a jar is presented exhibiting as a single design the leading feature 45 already indicated.

We claim—

The design for a packing jar herein shown and described.

In testimony whereof we affix our signatures in presence of two witnesses.

JOHN P. SHERWOOD.

SYLVESTER H. HUNTER.
